DRINKING MUG

George Dodge, Westport, N.Y., assignor to Dipak
Manufacturing Co. Inc., Westport, N.Y.

Filed Oct. 4, 1972, Ser. No. 298,753

Term of patent 14 years

Int. Cl. D7—01

U.S. Cl. D7—9

FIG. 2

FIG. 1

FIG. 4

FIG. 3

FIG. 1 is a perspective view of a drinking mug showing my new design.

FIG. 2 is a cross-sectional view taken on the line 2—2 of FIG. 1.

FIG. 3 is a side-elevational view, the opposite side being a mirror image of the side shown; and

FIG. 4 is an end-elevational view.

I claim:

The ornamental design for a drinking mug, substantially as shown and described.
